WRITING IMPLEMENT

Robert W. Ritzert, Dayton, Ohio, assignor to
 Rolin Manufacturing Company, Dayton, Ohio,
 a corporation of Ohio

Application January 6, 1932, Serial No. 584,955

8 Claims. (Cl. 281—5)

My invention relates to writing implements, and particularly to a pencil and pen having a receptacle or magazine to receive and support a roll of writing material, the free end of which may be readily projected and retracted from the side of the pencil or pen, so that it may be grasped by the user to have any desired amount of the paper from the roll withdrawn and torn off for the purpose of having notes or any other memorandum written thereon.

One object of the present invention is to provide such a pencil or pen with an outer barrel or casing and an inner barrel or magazine, the latter being constructed to receive and support a roll of writing material, blotting paper, or other matter.

Another object of this invention is to provide a positive locking feature for the paper roll to prevent the paper from being unrolled therefrom when the withdrawn end thereof is being torn off by the user.

Another object is to arrange the barrels for relative rotary movement; for readily side loading of new rolls; for automatically projecting the free end of the roll from the side of the pencil or pen; for automatically retrieving the free end of the paper which has been projected, should the user decide not to use any of the paper after having projected the end thereof; for positively locking the paper upon the closing of the opening in the outer barrel; and for the reception of any other article which the user may desire to place within the pencil or pen.

Another object is to provide a flexible or resilient support for the paper roll.

A still further object is to provide a pencil or pen with a side loading means for the reception of a roll of paper to be written on, a roll of blotting paper, a calendar roll, or any other matter or article which it is desired to carry therein.

With these and incidental objects in view my invention consists of certain novel features of construction and combinations of parts, the essential elements of which are set forth in appended claims, and a preferred form of embodiment of which is hereinafter described with reference to the drawing which accompanies and forms part of this specification.

Of said drawing:

Fig. 1 is a view of my novel pencil showing the projected end of a paper roll.

Fig. 2 shows the pencil with the end of the paper withdrawn and ready to be torn off by the user.

Fig. 3 is a view, partly in section, of my novel pencil.

Fig. 4 shows the inner barrel or magazine.

Fig. 5 is a bottom view of the inner barrel.

Fig. 6 is a top view of the inner barrel.

Fig. 7 is a section on line 7—7 of Fig. 4.

Fig. 8 illustrates the stopping or controlling disk for limiting the movement of one barrel while the other is being rotated.

Fig. 9 shows the friction spring associated with the barrels.

Fig. 10 is an edge view of said spring.

Fig. 11 is a section on line 11—11 of Fig. 1, showing the exposed paper.

Fig. 12 is a section on line 12—12 of Fig. 3, showing the normal positions of the parts.

Fig. 13 shows a roll of paper wound tight to form its own core, and the formation of the free end of the paper roll after the same has been fully retracted.

Fig. 14 shows the outer barrel.

Fig. 15 is a section on line 15—15 of Fig. 14.

Fig. 16 illustrates the trunnioned cup for supporting one end of the paper roll.

Fig. 17 is an edge view of said cup.

Fig. 18 shows an application of my invention to a fountain pen.

Detailed description

My improved pencil is designed to provide the user with writing material upon which he may make notes or memorandum whenever the occasion demands.

The casing of the pencil includes a hollow tip 30 having a shouldered tenon 31 snugly fitted in the lower end of the outer barrel 32 (Fig. 3); and an inner barrel or magazine 33 having one end projecting out of the top of the outer barrel 32 over which end is frictionally fitted a cap 34. The shouldered tenon 31 and the lower inside of the outer barrel 32 may be threaded for the purpose of securing the tip 30 to the barrel 32 if desired.

A writing lead 35 projects from the end of the tip 30. Such lead is carried and controlled by any suitable mechanical means 36 represented herein by dot-and-dash lines. An extra lead magazine 37 may also be inserted in the pencil tip 30. An eraser 38 is inserted in the upper end of the inner barrel 33. The upper end of the inner barrel 33 has several saw slots 39 to provide for a tighter fit for both the eraser 38 and the cap 34. Four such slots 39 are shown, but the number may be increased or decreased as necessity demands.

The outer barrel 32 has an aperture 40 (Figs. 1, 2, 11, 12, 14 and 15) and the inner barrel 33 has an aperture 41 (Figs. 1, 4, 7, 11 and 12) which apertures permit side loading of a paper roll 42 or any other kind of material such as blotting paper, calendar roll, or other article which the user may desire to carry therein.

The inner barrel 33 has a plug disk 45 near its upper end tightly fitted therein. This disk 45 may be made integral with the barrel 33 if desired. This disk 45 has a hole 46 through which projects one end of a compression spring 47, the other end of which is snugly fit within a cup 48 adapted to slide in the barrel 33. The cup 48 has a trunnion 49 to support one end of the paper roll 42. This paper roll 42 may be wound tight to form its own core as shown in Fig. 13 or it may be wound on a separate core 50 indicated by dotted lines in Fig. 2.

Tightly fitted in the lower end of the barrel 33 is a plug 60 (Figs. 3, 4, 5 and 7) having a recess 61, a tenon 62 and a tapped hole 63. A pin 64 is also driven in the end of the tenon 62. This plug 60 may also be made an integral part of the barrel 33.

The outer barrel 32 has a plug disk 65 (Figs. 3, 14 and 15) snugly fitted therein and having a hole 66 to receive the tenon 62. This disk 65 may also be made integral with the barrel 32 if desired. A pin 67 carried by the disk 65 cooperates with a stop or control plate 68 having a hole 75 to fit over the pin 64 on the tenon 62, and a hole 76 through which projects a screw 77 tapped into the hole 63.

The screw 77 has a trunnion 78 to support the lower end of the paper roll 42. A C-shaped friction spring 79 (Figs. 9, 10 and 12) lies in the recess 61 and on top of the plug disk 65 to maintain a constant friction between the two barrels 32 and 33, thus holding the barrels in their normal positions (Fig. 12) and also in any other positions to which they may be moved by rotation thereof.

The control plate 68 has two shoulders 85 and 86 (Figs. 8 and 12) adapted to contact the pin 67, the shoulder 85 contacting said pin 67 when the parts are in their normal positions (Fig. 12) wherein the unopen section of the barrel 33 closes the aperture 41 in the barrel 32, and the shoulder 86 contacting the pin 67 when both or either of the barrels 32 and 33 have been rotated to a position where both openings 40 and 41 coincide or register with each other for the purpose of reloading the pencil with a new paper roll 42.

When a full roll 42 is in the pencil and the opening 41 in the outer barrel 32 is closed by the unopen section of the barrel 33 the parts are then as shown in Fig. 12. The spring 47 (Fig. 3) forces the cup 48 towards the bottom to hold the roll 42 rotatably on the trunnions 49 and 78, and the spring 79 creates sufficient friction between the under side of the head of the screw 77 and the face of the control plate 68 to maintain the barrels 32 and 33 in the positions shown in Fig. 12, thus preventing the paper end 87 from being projected from the opening 41, such end 87 being formed as shown in Fig. 13 and held between the inner surface of the barrel 32 and the outer surface of the barrel 33 between an edge 89 of the opening 41 of the outer barrel 32 and an edge 90 of the opening 40 of the inner barrel 33.

When the user desires to use some of the paper for notes of memorandum the end 87 of the paper may be projected by rotating either the

outer barrel 32 or the inner barrel 33, or by rotating both barrels simultaneously.

To rotate the inner barrel 33 the user holds the outer barrel 32 rigid and grasps the cap 34, which is snugly fitted over the upper end of the inner barrel 33, and turns said cap 34 to substantially the position shown in Fig. 11, whereupon the paper end 87 is projected as here shown. The user then draws out the required amount of paper after which he rotates the barrel 33 back to the position shown in Fig. 12 which retracts a small amount of paper and locks the same between the edges 89 and 90. The projected and drawn-out portion of the paper may then be torn off against the edge 89 leaving no portion of the paper exposed.

If the user, after rotating the barrel 33 to the position shown in Fig. 11, whereby the paper end 87 is projected as shown, should decide not to draw any paper from the roll, he merely rotates the barrel 33 back to the position shown in Fig. 12. Such return of the barrel 33 to the position shown in Fig. 12 retracts the paper end 87 back to unexposed position between the edges 89 and 90 and it takes the formation shown in Fig. 13.

The paper end 87 may be projected and retracted by holding the cap 34 rigid and rotating the outer barrel 32, or both the cap 34 and the barrel 32 may be rotated simultaneously.

In Fig. 18 I have shown my invention applied to a fountain pen 95. The outer barrel is designated 96, the inner barrel 97 and the cap 98. The parting line between the cap 98 and the barrel 96 is indicated at 99. The barrels 96 and 97 are constructed substantially the same as the barrels 32 and 33, and project and retract the paper end 87 from the roll 42 in the manner described above.

While the form of mechanism herein shown and described is admirably adapted to fulfill the objects primarily stated, it is to be understood that I do not intend to limit or confine my invention to the one form or embodiment preferred or to the one modification shown herein, as my invention is susceptible of embodiment in various forms, all coming within the scope of the claims which follow.

What is claimed is:

1. In a writing implement, the combination of a barrel having an aperture through which a pre-wound roll of paper may be passed; a cylinder inserted in one end of said barrel and having an opening to receive said pre-wound roll of paper, said cylinder rotatable to close the aperture in the barrel and grip the free end of the paper to facilitate its being torn off against the edge of the aperture in the barrel; means connected to the cylinder to facilitate turning the same; and means including a shouldered member connected to said cylinder and a projection on the barrel to limit the movement of the cylinder in both directions of its rotary movement.

2. In a writing implement, the combination of an outer barrel and an inner barrel, each barrel having an aperture, the unopen section of the inner barrel normally closing the aperture in the outer barrel; means to hold the barrels in such normal position; a member in the outer barrel having an opening; means on the inner barrel projecting into said opening in the member in the outer barrel; means to retain said barrels in such longitudinal relationship; a control device associated with the inner barrel; said device including a disk having a portion of its

- periphery of a lesser radius than the remaining portion to form opposed shoulders and a projection on the member in the outer barrel co-operating with said control device to limit rotary movement of the inner barrel in both directions. 5
3. A paper roll carrying device including two barrels one within the other and rotatable relatively to each other in opposite directions, each barrel having an opening to permit side loading of a pre-wound paper roll, the openings being so arranged that the roll is normally concealed, relative rotation of said barrels in certain directions allowing the free end of the paper to project out of the openings, relative rotation of the barrels in reverse direction or directions retracting the projected end of the paper to a position fully concealed. 10
4. The combination of an outer barrel and an inner barrel, each barrel having an opening in the side thereof; a slidable member in the inner barrel to support one end of a paper roll; means to limit the movement of said member; a fixed member on the inner barrel; a fixed member in the outer barrel; a projection on the last named member; a control member having its periphery formed by different radii; and a device to secure the control member to the fixed member on the inner barrel and to support the opposite end of the paper roll. 15
5. The combination of an outer barrel and an inner barrel, each barrel having an opening in the side thereof through which a roll of paper may be passed into the inner barrel; a slidable member in the inner barrel to support one end of the roll of paper; means to limit the movement of the slidable member; a fixed member in the inner barrel; a fixed member in the outer barrel; a projection on the last named member; a shouldered control means to limit rotary movement of said barrels; friction creating means intermediate the two fixed members; means on the fixed member in the inner barrel for locating the control means; and means for securing the control means to the fixed member in the inner 20
- barrel and for supporting the opposite end of the roll of paper. 5
6. A cylindrical device comprised of an outer rotatable barrel and an inner barrel each having an opening in the side thereof either barrel being rotatable with respect to the other to facilitate side loading of a roll of material and to form a crimp in the free end of the paper when it is pinched between the edges of the two barrels when the opening is closed; resiliently operated means to retain the roll of material within the inner barrel; and means to centralize the roll of material within said inner barrel. 10
7. A cylindrical device adapted to carry a roll of material, said device being comprised of an outer rotatable cylinder and an inner cylinder each having an opening in the side thereof so arranged when the openings register with each other as to permit of the ready insertion of a pre-wound roll of material through said openings, said cylinders being so constructed as to allow the free end of the roll of material to be exposed upon turning motion of either cylinder with respect to the other to place said free end of the roll accessible to the operator, to draw in 25 the free end of the roll to an inaccessible position upon turning motion of either cylinder with respect to the other, to lock the roll against rotation when the free end is drawn out and severed therefrom by tearing the same along the edge 30 of the opening in the outer cylinder, and to prevent loss of the free end of the roll when the same is drawn in. 20
8. In a writing implement having an opening in the side of its casing; a rotatable member 35 within said casing, said member having an opening in the side thereof to receive a roll of paper; and control means in the casing for the member to limit the relative rotation of the member and the casing to a definite open position and to a 40 definite closed position, said control means comprising a disk connected to said rotatable member and a projection secured to said casing. 40
